PETROLEUM DISTILLATION

Frank J. Smith, Louisville, Ky., assignor to
Standard Oil Company, Chicago, Ill., a corpora-
tion of Indiana

Application October 15, 1937, Serial No. 169,129

7 Claims. (Cl. 196—73)

This invention relates to a process and apparatus for distilling petroleum oils and more particularly heavy residual petroleum oils. An object of the invention is to provide a method for controlling pipe still distillation and more particularly for controlling the operation of a two coil pipe still wherein two or more streams are separately heated in a single pipe still furnace. Another object of the invention is to regulate the 5 operation of a two coil pipe heater with maximum heat economy. Another object of the invention is to provide a method of controlling the temperatures obtained in a two coil heater by transferring heat from one coil to the stock charged 10 to the other coil in variable amount as desired to balance the respective coil outlet temperatures. Still another object of the invention is to obtain close control of the temperatures of two oil streams from a single pipe heating furnace without 15 the necessity of interfering with the combustion balance in the furnace. Another object of the invention is to provide a method of producing especially high quality asphalt from crude petroleum and other heavy petroleum products by 20 rapid evaporation of heavy oils therefrom without permitting decomposition of the asphalt which results in its being contaminated by relatively low boiling hydrocarbons. Other objects of the invention will be apparent from the following description.

My invention is illustrated by the accompanying drawing in which Figure 1 shows a schematic arrangement of one modification in which heat may be transferred from the oil entering the second coil to the charge of the first coil in a two coil heater. Figure 2 is a diagram showing another modification of my process in which heat from the products of the second coil is transferred to the charge of the first coil in a two coil 30 pipe heater.

Referring to Figure 1, topped crude petroleum which has been distilled substantially free of gasoline and which may be at a temperature of 375° F. for example, is introduced by line 10 to heating coil 11 in pipe heating furnace 12 where the temperature of the oil may suitably be raised to 700° F. in the transfer line 13. The heated oil is transferred to fractionating tower 14 where light fractions are removed, including naphtha and kerosene. The unevaporated oil is withdrawn from the base of tower 14 by line 15 and pump 16 through exchanger 17 and thence by line 18 to the second coil 19 in pipe furnace 12. The oil may be charged to coil 19 at a temperature 40 of about 550 to 650° F. and discharged by trans-

fer line 20 at a temperature of about 750° F. The hot oil and vapors are introduced into fractionating tower 21. This tower is preferably operated under vacuum, for example 50 mm. mercury absolute pressure and gas oil and lubricating oil 5 fractions may be withdrawn as desired. For example, gas oil vapors may be withdrawn by vapor line 22 and a lubricating oil fraction may be trapped out as a side stream by line 23. The unevaporated residue may be withdrawn by line 24 10 and employed in the manufacture of asphalt or as a heavy residual fuel oil.

A portion of the stock flowing through line 10 may be diverted through heat exchanger 17 by partially closing valve 25 and opening valve 26 15 in line 27. By regulating valves 25 and 26 any desired amount of the stream flowing in line 10 may be thus diverted through the heat exchanger 17 where it absorbs part of the heat of the oil flowing through line 18. The temperature of the 20 oil in line 10 may thus be raised 25 or 50° for example, thereby reducing the heat duty on coil 11 and increasing the heat duty on coil 19. As a result of the change in the heat duty of coils 11 25 and 19 the outlet temperature of coil 19 will be reduced and that of coil 11 will be increased a proportionate amount without altering the firing of the heater 12. Of course if the temperatures of both coils are too low or too high these may be corrected by regulating the firing in the conventional manner. This device therefore provides a very convenient method of controlling the outlet 30 temperatures of the respective coils 11 and 19 and thereby regulating the operation of fractionating towers 14 and 21 within narrow limits. If 35 desired, I may employ automatic means for regulating valves 25 and 26 to maintain a constant temperature in either line 13 or line 20, the firing of the heater 12 being controlled by the temperature of the other line.

Referring to Figure 2, crude oil may be heated by passing through reflux exchangers 40 and 41 and topped in the customary topping still to remove gasoline. The topped crude is introduced by line 42 leading to exchanger 43 and is then 45 conducted by line 44 to pipe heater 45 where it flows through economizer 46 and thence through radiant heating coils 47, discharging by transfer line 48 into flash drum 49. If desired, a portion of the heated stock in line 44, leaving 50 exchanger 43 may be vaporized by flashing in a flash drum (not shown) and the vapors conducted directly to fractionator 51 later described.

The temperature of the oil flowing through line 48 may be about 690° F. Vapors of gasoline, 55

oil, kerosene and naphtha are withdrawn from the flash drum by line 50 and fractionated in tower 51, light gas oil being withdrawn at the bottom by line 52 and naphtha or kerosene vapors being withdrawn by line 53 leading to a condenser not shown.

Unevaporated oil is drawn from the base of flash drum 49 by line 54 to accumulator 55, the pressure of which is balanced against the flash drum pressure by line 56. Oil from the base of accumulator 55 flows by line 57 and pump 58 to heating coil 59 within the heater 45. Steam may be admitted by line 60 to the stream entering heating coil 59 to increase the velocity, reduce coking and corrosion and otherwise facilitate the distillation of the heavy stock flowing through this coil. The temperature of the oil introduced to the coil may be about 550 to 675° F., depending principally on the temperature of the oil in line 48 and the extent of distillation in flash drum 49.

Hot oil is conducted from coil 59 by line 61, suitably at a temperature of about 750° F. to fractionating tower 62 wherein light constituents are evaporated from the asphalt and vapors refluxed in the upper section of the tower by the reflux coils 40 and 41. Uncondensed vapors are withdrawn by line 63 leading to a condenser not shown.

In the tower 62 reflux is largely prevented from passing to the bottom by trap-out plate 64 from which heavy gas oil and/or lubricating oil are withdrawn by line 65. If desired additional trap-out plates may be provided in the upper section of tower 62 to remove other fractions, such as light lubricating oils. When not employed for the manufacture of lubricating oils the stream withdrawn by line 65 may be subjected to cracking for the production of gasoline.

A portion of the heavy residual oil in the base 40 of tower 62 may be collected by trapout plates 66 and conducted by pump 67 and line 68 to heating coil 59, preferably by passing first through heating coil 69, which discharges into the inlet 45 of coil 59. The purpose of returning part of the asphalt to the heater is to increase the amount of heat introduced into tower 62 by the stock in line 61, thus facilitating the operation of the tower by permitting higher reflux ratios resulting in better fractionation and separation of heavy 50 distillates from the asphalt. Recycling of residues in this manner has been previously practiced in the vacuum distillation of lubricating oils as described in Bahlke and Stockdale Patent 1,997,675 and is not a part of my invention. The 55 amount of residual oil which may be recycled in this manner may be about 20 to 60% of the unevaporated residue in tower 62.

Asphalt which overflows trapout plate 66 passes to the base of tower 62 where it may be 60 subjected to the stripping action of steam introduced by line 70, the purpose of the steam being to strip from the asphalt as completely as possible all lower boiling oils which adversely affect the properties of the asphalt if allowed to remain 65 therein. I prefer also to operate tower 62 at a reduced pressure, for example 50 mm. mercury absolute to facilitate the removal of oils from the asphalt and avoid the necessity of operating the fractionating tower at a higher temperature 70 which would increase the decomposition of the asphalt with the formation of lighter oils in situ.

When operating tower 62 under vacuum the asphalt may be withdrawn from the bottom thereof by pump 71 and line 72 at a temperature 75 of about 600° F. The asphalt is immediately

cooled by passing through exchanger 43 and discharged from the process by line 73. The purpose of the immediate cooling of the asphalt stream as indicated above is to reduce the temperature below the decomposition point, for example about 450-500° F., and thus prevent the formation of light oils therein by thermal decomposition since light oils present in asphalt have been found to cause objectionable staining when the asphalt is used for certain purposes, such as in the manufacture of roofing materials. Their presence in amounts of only fractions of 1% can be readily detected by the so-called "stain test" which asphalt must pass before they are acceptable for the purposes indicated. Various methods may be 10 employed for testing the staining characteristics of the asphalt as placing a sample of the asphalt in contact with paper, talc, etc. Applicant prefers to employ the following test: A sample of asphalt is placed in a shallow flat dish and melted to form a layer. A thin layer of talc powder is then placed on the asphalt and the dish placed in an oven at a temperature of 140° F. for 48 hours. The sample is then removed from the oven, excess talc discarded and the color of the talc layer adhering to the asphalt is examined. The discoloration of the white talc layer is a direct indication of the staining characteristics. Two or more specimens of asphalt may be compared in this way.

In order to balance the operation of coils 41 and 59 and maintain the desired control of flash drum 49 and fractionating towers 51 and 62 I continuously withdraw a portion of the asphalt from the cooled stream passing through line 73 by means of valved line 74 leading to accumulator 55. This may be conveniently accomplished by regulating valves 75 and 76. The temperature of the oil withdrawn may, for example, be about 425° F. The amount of asphalt recycled in this manner is usually relatively small and will ordinarily be about 5 to 20% of the total asphalt in tower 62. By increasing or decreasing the amount of asphalt by-passed in this manner the temperature in transfer line 61 may be respectively reduced or raised as desired. When maximum reduction of the transfer line temperature in 61 is required it may be desirable to slow down pump 67 with the result that the asphalt recycled to coil 59 is returned at a lower temperature, for example 425° F., instead of 600-650° F. which is the approximate temperature of the oil in line 68. Thus my process provides a very sensitive means of heat control which responds to the mere turning of a valve. At the same time no heat is wastefully discarded from the system since the heat removed from the oil recycled in line 74 is all absorbed by the oil charged through line 44 to heating coil 47. By increasing the amount of asphalt recycled through line 74 and reducing that recycled through line 68 I am thus enabled to increase the heating duty of coil 59 and reduce that of coil 47 with the result that the transfer line temperatures in lines 61 and 48 are lowered and raised respectively without changing the firing of the furnace.

Instead of introducing the oil from line 74 into accumulator 55 I may, of course, introduce it directly into line 57 at the inlet of coil 59 but I prefer to introduce it into accumulator 55 where any sudden change in the amount of oil by-passed in this fashion is evened out. If desired, I may return by valved line 77, a portion of the cooled asphalt from line 73 to the base of tower 62 as a

flux to lower the temperature therein and prevent decomposition and coke formation.

Having thus described my invention, what I claim is:

5. 1. In the process of distilling petroleum oils wherein the oil is heated in a restricted stream in a heating zone, a portion of the oil is evaporated and the unvaporized oil is further heated in another restricted stream in the said heating zone 10 and then another portion of the oil is evaporated, the improvement comprising controlling the temperature of the oil from each stream by exchanging heat between the oil to be heated in one of said restricted streams with the oil introduced into said other restricted stream.

2. In the distillation of petroleum oils wherein oil is supplied to two separate fractionating zones from two separate restricted streams located in a single heating zone, the first of which restricted 20 streams is supplied with hot feed stock and the second with a cooler stock, the improvement comprising reducing the temperature of the oil discharged from said first restricted stream charged with hot feed stock by exchanging heat between 25 the hot feed charged thereto and the cooler stock charged to said second restricted stream.

3. The process of claim 2 in which said heat exchange is accomplished by by-passing a regulated portion of the cooler feed stock of said 30 second restricted stream into heat exchange relation with the hot feed stock of said first restricted stream and then again commingling said portion with the charge to said second restricted stream.

35. 4. In the process of distilling residual petroleum oils wherein a stream of said oil is heated in a first heating zone, partially distilled, the undistilled residue is heated in a second heating zone to a higher temperature and then further distilled said heating zones being both supplied with heat from the same source, the improvement comprising regulating the temperature of the oil contained in said first heating zone by transferring regulated amounts of heat to the oil 40 entering said first heating zone from the oil charged to said second heating zone.

45. 5. In the process of distilling residual petroleum oils wherein a stream of said oil is heated in a first heating zone, partially distilled, the undistilled residue is heated in a second heating zone to a higher temperature and then further distilled said heating zones being both supplied with heat from the same source, the improve- 50

ment comprising lowering the temperature of the oil leaving said second heating zone by transferring heat from the oil entering said second heating zone to the oil entering said first heating zone.

6. The process of producing from crude petroleum, asphalt having a satisfactory "stain test" which comprises removing from said crude petroleum lighter fractions and light gas oil by heating in a continuous restricted stream and flashing off said light fractions, returning the unevaporated residue from said flashing operation to a second heated stream supplied by heat from the same combustion gases employed in heating said first mentioned restricted stream, conducting the heated oil from said second heated stream to a fractionating zone wherein heavy oils are evaporated from asphaltic constituents, withdrawing and immediately cooling said asphaltic constituents to prevent thermal decomposition thereof, employing a variable amount of the heat removed from said asphaltic constituents to regulate the temperature of the crude petroleum charged to said restricted stream first mentioned, and returning a regulated portion of said cooled asphalt to the stock charged to said second heated stream for controlling the outlet temperature thereof.

7. In the process of producing asphalt of desirably low stain characteristics wherein a stream of crude petroleum is heated in a first heating zone, light fractions, including light gas oil, are removed by evaporation and the stream of unevaporated oil is heated to a higher temperature in a second heating zone located in the same furnace with said first heating zone, the hot products from said second heating zone are distilled under vacuum in a fractionating zone where heavy oil constituents are evaporated from the asphalt and the asphalt is withdrawn from the fractionating zone and immediately cooled by 40 heat exchange with said stream of crude petroleum charged to said first heating zone to prevent thermal decomposition thereof, the improvement comprising recycling a portion of the hot asphalt from said fractionating zone to the inlet 45 of said second heating zone, recycling a portion of the cooled asphalt withdrawn from said fractionating zone to the inlet of said second heating zone and controlling the temperature of the oil discharged from said second heating zone by 50 regulating the relative amounts of hot asphalt and cooled asphalt recycled thereto.

FRANK J. SMITH.
